(54) **TRUSS, SPRING**

(76) Inventor: **Henry Reid**

Henry Reid,
Letters Patent.

The Schedule referred to in these Letters Patent, and so making part of the same containing a description in the words of the said Henry Reid himself of his improvement in helping traps.

Be it known that I, Henry Reid of the city of Augusta in the County of Richmond and State of Georgia have invented a new and useful improved Spring Trap, for the immediate and permanent relief and probable cure of those who are afflicted with inguinal, scrotal and umbilical hernial protrusion and the following is a full and exact description thereof. This improved independent spring trap which I have invented consists of a steel plate about three fourths of an inch broad, and about one twelfth of an inch thick at each end, with a gradual diminution of the thickness from each end to the middle of the plate. On each end of the plate three small holes are drilled in the form of an equilateral triangle between which a neck somewhat rounded of one inch in length is formed. The side of the plate next to the trap is rounded, that is, the corners rounded; the trap extends from the center of the abdomen and runs on the right side in the oblique direction around the loins and back, and terminates on the ^{center of the} abdominal ring on the left side. This plate is curved so fit the patient so as to make the perforated end rest upon the abdominal rings. The whole plate (except those holes at each end) must receive a good spring temper. The post is an oval block of wood, for a man of common stature in the proportion of three inches long two inches broad, and one inch thick convex on the one side and plane on the other side,

resembling very much the one half of a goose egg, divided longitudinally. The size of the block however must be adapted to the necessity of the case according to the judgment of the surgeon in attendance. The block is attached to the spring by small wood screws, three eighths of an inch in length; the plane side of the block comes in contact with the abdomeal end of the spring the large end of the block is next to the pubis. A short curved spring of similar strength with three small holes drilled at each end in the form of an equilateral triangle, extending from the abdominal block to the umbilicus with a circular block in the proportion of two inches diameter, and one inch thick, or even one on one side and plane on the other may be added in all cases of umbilical hernia; The size of this block also must be adapted by the surgeon to the necessity of the case; both springs are covered neatly with a strip of soft flannel. This block differs from Halls, Musters, Staggers and all others in passing from one side in behind the pelvis and around the other groin, and passes with equal force on the soft part above the brim of the pelvis on each side before with a lateral and inward pressure, having its points of pressure before the anterior edge of the lateral parts of the great pelvis so as to ensure its retention in its place. It differs from Halls and Musters in the peculiar shape of the block by which the immediate pressure is made, and in the immobility of the blocks, and in the pressure being made by blocks instead of pads or cushions. It differs from Staggers in having simply spring power and that so adjusted to the parts as to retain its adjustment without the aid of belt, buckle and straps or any other means except the spring power.

Application. - If the patient be afflicted on one side only, let a soft pad of flannel be attached to the end of the trap, which is to come in contact with the bound abdominal ring, then let the trap be applied by the surgeon and the wood block placed so that the upper side of the ring will coincide with the centre of the defected abdominal ring and its lower side with the nose of the bone immediately to the

ring. The pressure must never be so great as to produce external inflation; the pressure can be graduated by the surgeon or patient binding in or out the untempered ends of the trap. In all cases block must be adjusted to the part before it is fastened to the spring. The umbilical spring is not necessary in common cases, but when used it must be carefully adjusted to the part afflicted and fastened by small wood screws to the abdominal block. It can be well for those who can afford it to have the convex side of the block covered with a thin plate of silver or gold. This thin plate ought to be smoothed and anointed with sweet oil once every month to prevent rust.

Advantages. This trap will suit equally well the afflicted of both sexes; it will be peculiarly useful to the accouchier in all cases of parturition complicated by hernia because its operation is without traps, which cannot be well applied in the latter stages of pregnancy or in labor, and will by its pressure prevent the necessity of an apistia or the use of one of the accouchiers hands for preventing parturition. It will not prevent attention to the ordinary business of life as its retentive power can be overcome by violent efforts only nor will it prevent sleeping in the most fashionable manner as it requires neither belt trap nor buckle to keep it in its proper place.

N.B. Let the surgeon get the exact size of his patient by passing a flexible wire around his body, and have the trap prepared accordingly. What I claim as my own invention and not previously known in the above described improved independent Spring Trap is that it: keeps from one abdominal ring, bound the loins & back to the other abdominal ring and maintains permanently equal pressure on the soft parts above the brim of the pelvis on each side, without the aid of belt trap buckle or any other appendage whatsoever, and I claim also the short curved spring passing from the groin to the umbilical abdominal ring.
